UNITED STATES PATENT OFFICE.

WILBUR G. HUDSON, OF NEWARK, NEW JERSEY, ASSIGNOR TO GUARANTEE CONSTRUCTION COMPANY, OF NEW YORK, N. Y., A CORPORATION OF NEW YORK.

CONVEYER-ELBOW.

1,044,181.

Specification of Letters Patent. Patented Nov. 12, 1912.

Application filed March 29, 1911. Serial No. 617,609.

To all whom it may concern:

Be it known that I, WILBUR G. HUDSON, a citizen of the United States of America, and a resident of Newark, in the county of 5 Essex and State of New Jersey, have invented certain new and useful Improvements in Conveyer-Elbows, of which the following is a specification.

In conveying materials by pneumatic conveyers, either by forcing a draft of air through a conveying duct or by inducing an air current by exhausting from an inclosed tank into which the conveyed material is received, a considerable amount of 15 abrasion has been found to occur at elbows or turns in the conveyer duct.

The object of my invention is to provide means for minimizing such abrasion and reduce the frequency of renewal of the abraded 20 parts.

In the accompanying sheet of drawings which forms a part of this application—Figure 1 is a longitudinal section through an inclosed elbow embodying my invention 25 on the line I—I of Fig. 2. Fig. 2 is a cross section on the line II—II of Fig. 1.

The invention is illustrated in connection with a flanged elbow cast with a pocket P at its bend. The mouth of the pocket is 30 substantially closed or bridged by a wear plate W for which manganese steel is a suitable material. The face of this plate is even with the mouth of the pocket, forms a continuation of the inner surface of the 35 elbow, and forms substantially all of that portion of the interior elbow surface which receives the impact of solid materials and from which they rebound in passing through

the elbow. The wear plate fits loosely in the pocket so that when struck it will yield back into the pocket and the force of impact will thereby be diminished. The wear plate is pressed inward by springs S S, and also by the pressure of the air which may be admitted behind it. Its inward movement 40 is limited by bolts B B, which project through the rear wall of the pocket. Nuts N N on the bolts and accessible outside the elbow secure the wear plates and serve as a means for its adjustment. The inside of 45 the bend of the elbow is provided with an opening which is closed by a plug O. Through this opening the wear plate can be inspected and removed and renewed when necessary. When there is a partial vacuum 50 inside the elbow, the air back of, or behind the wear plate forces it inward, and tends to hold it in place against the impact of 55 the material conveyed.

What I claim as new, and desire to secure 60 by Letters Patent of the United States, is—

1. The combination with an elbow provided with a pocket at its bend of a wear plate yieldably supported in the pocket, substantially as described. 65

2. The combination with an elbow provided with a pocket at its bend of a wear plate elastically supported in the pocket, substantially as described. 70

Signed at New York, N. Y., this 24th day of March, 1911.

WILBUR G. HUDSON.
